SCREEN LADDER JACK

Roy A. Davis, San Antonio, Tex.

Application August 4, 1934, Serial No. 738,564

2 Claims. (Cl. 248—210)

This invention relates to supporting means for articles which are to be painted such as window sashes, screens, blinds, or the like.

An object of this invention is to provide an exceedingly simple detachable supporting means which may be readily mounted on a step ladder, the device being so constructed that it can be mounted on either the side of the ladder or on the step of the ladder and when so mounted will hold or support articles with the upper ends of the articles leaning against the upper portion of the stepladder.

A further object of this invention is to provide in a device of this kind, means whereby the article to be supported will be prevented from slipping off of the support while at the same time, the device will not cover a considerable portion of the article and thereby prevent painting or other work being performed on the article.

The above and various other objects and advantages of this invention will in part be described and in part be understood from the following detailed description of the present preferred embodiment, the same being illustrated in the accompanying drawing wherein:—

Figure 1 is a fragmentary vertical section of a stepladder of conventional construction having a device constructed according to the preferred embodiment of this invention mounted thereon, the device being shown in side elevation and a window sash being mounted on the device, the window sash being shown in fragmentary vertical section.

Figure 2 is a horizontal section through the front portion of a stepladder and showing the supporting member in top plan, the supporting member engaging the side of the ladder.

Figure 3 is a perspective view of the device. Referring to the drawing wherein like numerals of reference designate corresponding parts throughout the views, the numeral 10 designates generally a stepladder of conventional construction which is provided with rungs or step members 11 secured to side members 12 and which are held in upright position by means of a swingable leg structure 13 shown here in fragmentary side elevation. This stepladder structure is of conventional construction and is shown here only as one means with which the hereinafter described invention may be used.

In order to support a sash, screen, blind or other article to be painted, repaired or otherwise serviced, I have provided a supporting member, generally designated as 14. This supporting member 14 comprises an elongated bar 15 pref-

erably of straight form which is provided at its inner end with a substantially U-shaped clamping member 16 engaging about the step or rung 11. The outer or free end of the bar 15 is provided with a laterally extending lug 17 against which the bottom of the sash or other article designated S is adapted to engage. Preferably, there are at least two of these supporting members 14 mounted on the step or rung 11 one adjacent each side of the stepladder.

Where the step 11 is so constructed that it is not possible or convenient to have the U-shaped clamping member 16 mounted thereon, the clamping member 16 can be engaged with the side member 12 of the step ladder with the bar 15 disposed on the inner side of the side member 12 and engaging the top surface of the rung or step member 11. When in this position, the sash S is held against outward sliding movement by one of the opposed lugs 18 disposed on the outer end of the bar 15. The lugs 17 and 18 form a substantially T-shaped outer end for the bar 15 and provide a means whereby the supporting member 14 may be easily and conveniently mounted on ladders of various types.

In the use of this device, where the stepladder has a step or rung 11 which does not have a rib or brace on the bottom thereof to prevent the engagement of the clamping member 16 therewith, the device is mounted between the sides 12 after the manner shown in Figure 1. Preferably, there are at least two of these supporting members mounted on the step 11, one adjacent each end thereof. Where it is not possible to slide the clamping member 16 over the step 11 as shown in Figure 1, due to braces or other means below the step 11, the supporting member 14 can be mounted as shown in Figure 2, and in view of the opposed lugs 18 on the outer end of the bar 15, the device can be turned in any desired manner 40 preferably with the bar 15 on the inside of the side bar 12 of the ladder.

Through the use of the device herein disclosed, it is possible to support articles such as sashes, screens, blinds or the like, on a stepladder so 45 that these devices can be painted, repaired or the like, and the articles can be supported at a convenient height.

What is claimed is:—

1. A means for supporting sashes or like articles on a stepladder, comprising an elongated bar, a T-shaped outer end portion integral with the bar and disposed at right angles to the length of the bar and adapted to engage the lower edge of an article to hold the article from sliding off 55

of the bar, and a clamping means carried by the other end of the bar for detachably mounting the bar on the stepladder.

2. A means for supporting sashes or the like on a stepladder, comprising a pair of elongated bars, laterally extending right angularly related

lugs integral with an end of each bar, and a U-shaped clamping member integral with the other end of each bar and adapted to engage the stepladder for holding the bar in substantially horizontal position.

ROY A. DAVIS.
